INVENTOR,

James Turner

UNITED STATES PATENT OFFICE.

JAMES TURNER, OF COUDERSPORT, PENNSYLVANIA.

FOLDING TABLE.

SPECIFICATION forming part of Letters Patent No. 399,221, dated March 5, 1889.

Application filed January 19, 1887. Serial No. 224,804. (No model.)

To all whom it may concern:

Be it known that I, JAMES TURNER, a citizen of the United States, residing at Coudersport, in the county of Potter and State of Pennsylvania, have invented a new and useful Improvement in Folding Tables, of which the following is a specification.

The object of the invention is to provide a "knockdown" table of novel construction, adapted to be packed in a small space for transportation.

The invention consists in the features of construction and combination of parts herein-after fully described, and pointed out in the claim.

In the drawings, Figure 1 represents my improved table partly taken apart. Fig. 2 shows the table put together for use; and Figs. 3, 4, and 5 illustrates parts in detail.

S represents the supporting-shaft of the table, provided with two slotted rings or collars, U and K. The shaft S is provided with two pins, P, adapted to enter openings in the table-top B, which latter is also held by hooks J, engaging eyes (not shown) on the under side of the top.

A A represent braces for supporting the hinged leaves a of the table. These braces are each provided with a hinge, O, Fig. 1, one

leaf of which is designed to be secured within one of the slots of the ring or collar U. The braces A are also provided with the double hooks H, engaging eyes e e, and similar eyes (not shown) under the table-top.

L represents the supporting-legs of the table. These legs fit within the slots or recesses of the collar K, and are connected by hooks J and eyes e to the shaft S. The legs are also secured by double hooks H, engaging eyes secured to the legs and shaft S, as shown.

It will be apparent that my table may be readily taken apart and as readily put together again, and also that it will be secure and firm in structure when properly jointed and connected.

45

I claim—

The combination, with the shaft having a central slotted or recessed collar, U, a lower recessed collar, K, and pins P, of the table top and leaves, the braces A, hinged to the collar U and provided with hook-and-eye connections, and the legs L, fitting the recesses of the collar K and having hook-and-eye connections, substantially as set forth.

50 JAMES TURNER.
